CLAIM

The ornamental design for a gas distribution plate, as shown and described.

DESCRIPTION

FIG. 1 is a top-front isometric view of our new design for a gas distribution plate;

FIG. 2 is a top-rear isometric view of the gas distribution plate of FIG. 1;

FIG. 3 is a front view of the gas distribution plate of FIG. 1;

FIG. 4 is a rear view of the gas distribution plate of FIG. 1;

FIG. 5 is a left side view of the gas distribution plate of FIG. 1;

FIG. 6 is a right side view of the gas distribution plate of FIG. 1;

FIG. 7 is a top view of the gas distribution plate of FIG. 1; and,

FIG. 8 is a bottom view of the gas distribution plate of FIG. 1.

The portions of the gas distribution plate shown in broken line form no part of the claimed design.
